UNITED STATES PATENT OFFICE.

ADOLPH P. OSIUS, OF DETROIT, MICHIGAN.

DESIGN FOR AN ICE-CREAM DISHER.

54,221.

Specification for Design.

Patented Nov. 18, 1919.

Application filed July 29, 1919. Serial No. 314,141. Term of patent 14 years.

To all whom it may concern:

Be it known that I, ADOLPH P. OSIUS, a citizen of the United States, residing at Detroit, in the county of Wayne and State of Michigan, have invented a new, original, and ornamental Design for an Ice-Cream Disher, of which the following is a specification, reference being had to the accompanying drawing, forming part hereof.

Figure 1 is a side elevation of the ice cream disher; showing my new design;

Fig. 2 is a plan of the same.

I claim:

The ornamental design for an ice cream disher as shown.

ADOLPH P. OSIUS.
